UNITED STATES PATENT OFFICE.

ALFRED JOHN KEMUEL WILESMITH, OF LEIGH, ENGLAND, ASSIGNOR OF ONE-HALF TO
WILLIAM HENRY LEEKE, OF WORCESTER, ENGLAND.

APPARATUS FOR HEATING THE COMBUSTIBLE CHARGES OF INTERNAL-COMBUSTION ENGINES.

1,151,503.

Specification of Letters Patent.

Patented Aug. 24, 1915.

Application filed March 29, 1915. Serial No. 17,891.

To all whom it may concern:

Be it known that I, ALFRED JOHN KEMUEL WILESMITH, a subject of the Kingdom of Great Britain, residing at Pigeon House, 5 Leigh, in the county of Worcester, England, engineer, have invented certain new and useful Improvements in Apparatus for Heating the Combustible Charges of Internal-Combustion Engines, of which the following is a specification.

This invention has relation to apparatus for heating the combustible charges of internal combustion engines or facilitating the vaporization of fuels employed in connection with such engines, particularly the fuels of heavy density, such as paraffin, and refers to apparatus of the nature in which the induction pipe connecting the carbureter with the inlet ports of the engine passes 15 through or is partially inclosed within the interior of an exhaust chest or chamber in which the exhaust gases are precipitated or expelled and which is secured to the cylinder or cylinders. In this invention means 20 of a simple character are furnished for equalizing the heat on the inclosed induction pipe and thereby rendering the working of the engine more satisfactory and efficient.

According to the present invention the exhaust gases which impinge upon the part of the induction pipe within the exhaust chest leave the chest at or near both ends of same thereby equally distributing the heat 25 on the whole of the inclosed induction pipe.

In order that this invention may be clearly understood and readily carried into practice, reference may be had to the appended explanatory sheet of drawings, upon which:—

Figure 1 is a front elevation of a heating or vaporizing apparatus constructed in accordance with the present invention. Fig. 2 is a plan of the apparatus shown in Fig. 1, and Fig. 3 is a rear elevation of the apparatus. Fig. 4 is a longitudinal sectional view showing the inlet pipe as provided with a jacket and also having a mixer therein. Fig. 5 is longitudinal sectional view showing the inlet pipe arranged somewhat differently from in Fig. 4 and also having a different form of jacket, the mixer being omitted.

In accordance with the present invention, as applied to the internal combustion engine

of an automobile, the exhaust chest or casing 1 which is suitably attached to the cylinder heads, and is adapted to convey the exhaust gases from the said cylinders to the exhaust pipe is in this invention provided internally with the induction pipe 2 whereby same is considerably heated by the exhaust gases expelled from the engine. The induction pipe 2 which connects or communicates the carbureter with the inlet ports of the engine is of branched formation within the exhaust chest or casing in the case of a number of cylinders, each branch or arm leading or conducting the inlet gas as aforesaid to the inlet ports of the cylinders. By this arrangement it will be seen that the 50 exhaust gases play upon this branched or single induction pipe 2, (according to the number of cylinders) contained within the exhaust chest or casing 1. The exhaust chest or casing in this invention is preferably in the form of a somewhat rectangular or oblong box (as illustrated) into which the exhaust gases are precipitated and through which the induction pipe 2 passes. In the case of a four cylinder engine the exhaust chest or casing 1 may be in communication with the four cylinders by means of four short or suitably constructed exhaust pipes 3 and the exhaust gases leave the chest or casing through the medium of two 55 outlet pipes 4 which enter or are connected adjacent to the two closed extremities of the said chest 1, and said pipes may unite or join together in any position conveniently centrally of the casing and externally thereof and beneath, whence a single pipe or conduit 5 may be employed for conveying the exhaust gases to the silencer. The inlet or induction pipe 2 through which the gases pass may be in the form of U or fork 60 shaped member as shown, the most part of which is preferably disposed in the exhaust chest or casing 1. In the case of a four cylinder engine this forked induction pipe 2 is provided with two further branches upon each limb or arm thereof to supply the gas to the four cylinders, but these further branch pipes are preferably not incased within the chest 1. Obviously the induction pipe 2 and chest or casing 1 can be constructed for use with any engine independent of the number of cylinders thereof. As applied to a four cylinder engine, the

U-shaped induction pipe 2 may comprise a tube, the center part of which is disposed, either within or partly within the exhaust chest or casing 1 and the two extremities 5 are bent at right angles to the center part and pass through the casing 1 whence, as aforesaid, the said extremities 6 are again forked to supply the gas to the four cylinders. It will be understood that the cylinders 10 of the engine exhaust into the oblong and square section chest or casing 1 at a number of positions 3 along its length, and in order to enable a uniform pressure and flow or feed of the exhaust gases to be obtained, the chest or casing 1 may be bulged 15 or enlarged at positions 7, where the inclosed induction pipe 2 passes transversely therethrough so that an unrestricted passage is left from the one extremity of the casing 20 to the other, from the two extremities of which the exhaust gases are conducted away as aforesaid at 4.

The foregoing arrangement has been described more particularly with reference to engines having the inlet and exhaust ports on the one side of the engine cylinders, but when the inlet and exhaust are arranged on opposite sides, it will be seen that the chest or casing 1 may be disposed on the exhaust 30 side of the engine and the induction pipe 2 may be continued to the other side of the cylinders or engine, a portion of said induction pipe, of course, being disposed in the chest or casing for heating the ingoing gases. 35 Or in another arrangement in which the inlet and exhaust ports are on opposite sides of the engine, the chest or casing may be attached to the inlet side of the engine in which case the exhaust pipes 3 are extended 40 to the other side of the engine. Obviously the arrangement may be suitably constructed for use with overhead inlet, exhaust ports, and overhead inlet and exhaust ports.

The exhaust chest or casing 1 may be retained in position against the engine through the medium of bolts, pins or the like, and the exhaust and inlet ports or pipes of the said chest may be provided with fixed or movable flanges which are suitably machined and bear against or contact corresponding flanges provided upon the port or pipes of the engine, also said inlet pipe or pipes may be retained within the chest or casing through the medium of contacting 50 flanges. When the inlet pipes 2 have to pass to the opposite sides of the engine to which the chest or casing 1 is attached, a portion of the said inlet pipe is exposed to the atmosphere and on this account a mixer may, if desired, be employed and this mixer may be in the form of a number of concentrically disposed conical tubes 8 arranged closely together within the inlet pipe or pipes 2 as shown in Fig. 4, in such a manner that the gases when entering the cylinders pass

through the narrowest diameter of the cones 8, which cones are preferably fixed in a portion 9 in the inlet pipe 2. By the provision of these conical tubes, the velocity of the gases drawn through same is increased, and 70 said gases are completely mixed thereby providing a more satisfactory and effective combustible fuel in certain engines in which the gas tends to separate from the air due either to overheating or to partial cooling. 75

With further reference to the construction of the U-shaped induction pipe 2 within or partly within the chest or casing 1, the central part and two transversal extremities 6 may be entirely contained within the chest 80 or casing 1 to give a particularly large heating surface, or the central part may be disposed externally of the chest or casing, or said central part may be partly within and partly without the heating chest or casing, 85 as illustrated. It is preferable to employ a very short length of induction pipe 2 between the carburetor and the cylinder or cylinders, substantially the whole of which is heated. In instances in which only a short 90 portion of the induction pipe 2 is contained within the chest or casing 1, that portion may be of enlarged dimensions to give an increased heating surface, while if desired the inclosed portion of the induction pipe 2 or 95 the whole thereof may be of a different metal or alloy to that of the chest or chamber according to the temperature to which it is desired to raise the gases.

If desired, a jacket 16 may be provided 100 around the induction pipe 2 which is filled with oil or other liquid, such for example as ordinary petroleum, or material, which will not burn or carbonize at a temperature necessary to assist in the further vaporization or heating of the combustible charges passing through the induction pipe. This oil jacket or sheath provided around the induction pipe and around all or any of its branches may be constructed by providing 105 an external concentric tube around the induction pipe and filling the interior space between these two pipes with the oil or other liquid or material aforesaid. Such an oil jacket not only prevents the over-heating of 110 the combustible gases, but also co-operates with the arrangement of the inlet and outlet pipes provided by me to insure that the gases are heated evenly. As high powered engines generate more heat than lower powered engines, the nature of the oil or other liquid employed in the oil jacket would be varied according to the heat generated. 115 Thus it will be seen in operation that when the engine is running, the paraffin or other fuel passes through the carburetor which is provided outside the exhaust chest or casing. The atomized or carbureted gas then passes along the oil jacketed or other induction pipe when same is again assisted in 120 125 130

vaporization or prevented from condensation prior to same entering the engine. Conveniently this exhaust chest or casing which is usually constructed of cast iron 5 or admiralty gun metal may be formed as a unit with the annular heating device, induction pipe and the carbureter proper so that these parts can be removed from the engine and exhaust pipe as a unit for inspection or adjustment when so required.

If desired the induction pipe 2 within the exhaust chest or casing 1 may be jacketed by a second tube or tubes, such as 16, so as to form a vacuum between the said 15 tubes, or asbestos, mica, or other material 15 may be inserted between these tubes or around the induction pipe so as to prevent the burning exhaust gases of the engine overheating the induction pipe so that the 20 ingoing gases are ignited. Such jackets act similarly to the oil jacket in preventing undue heating of the combustible mixture.

Having thus described my invention and the manner in which the same is to be carried out, I claim:

1. In an apparatus of the class described in combination, an exhaust chest having two outlets, one at each end, an intake pipe for a combustion engine having two branches 30 passing through said chest intermediate said outlets, said chest having an inlet port for receiving the exhaust gases of the engine and placed intermediate said branches whereby the exhaust gases impinge on the 35 intake pipe and flow across said branches to said outlets.

2. In an apparatus of the class described in combination, an exhaust chest for an internal combustion engine having two outlets, one at each end, an intake pipe for said engine having two branches passing through said chest intermediate said outlets, said chest having an inlet port for receiving the exhaust gases of the engine and being so 45 arranged that the exhaust gases impinge on said intake pipe and flow across said branches to said outlets.

3. In apparatus of the class described in combination, an exhaust chest having an

outlet and having an inlet for receiving the 50 exhaust gases of a combustion engine, an intake pipe for said engine passing through said chest, said chest being so arranged that the exhaust gases impinge upon the inclosed 55 inlet pipe while the gases are passing from the inlet to the outlet of the chest, and a jacket surrounding said inlet pipe within said chest and adapted to prevent the overheating of the combustible gases, said jacket containing an oil which is not carbonized 60 at the temperature to which it is subjected in the exhaust chest.

4. In apparatus of the class described in combination, an exhaust chest having two outlets, one at each end, an intake pipe for 65 an internal combustion engine having two branches passing through said chest intermediate said outlets, a jacket surrounding said intake pipe within said chest adapted to prevent the overheating of the combustible gases within the intake pipe, said chest having an inlet port for receiving the exhaust gases of the engine and placed intermediate said branches whereby the exhaust 70 gases impinge on the intake pipe and flow across said branches to said outlets.

5. In apparatus of the class described in combination, an exhaust chest having two outlets, one at each end, an intake pipe for a combustion engine having two branches 80 passing through said chest intermediate said outlets, said chest having an inlet port for receiving the exhaust gases of the engine and placed intermediate said branches, said chest also being so arranged that the exhaust 85 gases impinge upon the inclosed intake pipe and cross said branches to said outlets, and a mixer in said intake pipe adapted to remix the combustible gases, said mixer comprising a number of closely disposed 90 conical tubes arranged in the intake pipes.

In witness whereof I have hereunto set my hand in the presence of two witnesses.

ALFRED JOHN KEMUEL WILESMITH.
